UNITED STATES PATENT OFFICE.

PETER D. GALARNEAU AND WILLIAM S. NEWTON, OF EAST ST. LOUIS, ILLINOIS.

DOOR OPENER AND CLOSER.

No. 898,865.

Specification of Letters Patent.

Patented Sept. 15, 1908.

Application filed December 13, 1907. Serial No. 406,275.

To all whom it may concern:

Be it known that we, PETER D. GALARNEAU and WILLIAM S. NEWTON, citizens of the United States, and residents of East St. Louis, in the county of St. Clair and State of Illinois, have invented new and useful Improvements in Door Openers and Closers, of which the following is a full, clear, and exact description.

10 This invention is an improvement in door operators of a mechanical and simple character for opening and closing the door, and has for an object to provide in a device of this nature a construction embodying a line 15 having two branches, one of which is attached directly to the door and the other passing to the door lock and connected therewith in such a manner that when the line is pulled the door if locked and closed, will be 20 unlocked and then opened, or if the door be opened, a pull on the line will close it.

A further object of the invention is to provide means for automatically locking and unlocking the door when in open position by 25 the operation of the door operating means.

Reference is to be had to the accompanying drawings forming a part of this specification, in which similar characters of reference indicate corresponding parts in all the views

30 Figure 1 is a front elevation of a door with our improvement applied thereto; Fig. 2 is a cross-section on the line 2—2 of Fig. 3, through the latching spindle, looking in the direction of the adjacent door knob; Fig. 3 35 is a fragmentary edge view of the door, showing the manner in which it is locked in open position; Fig. 4 is a section substantially on the line 4—4 of Fig. 1, looking in the direction of the arrow and showing a bracket and 40 suspended pulley forming a portion of the door operator; Fig. 5 is a sectional plan of a door opening and adjacent wall, showing the position of the parts of our improvement when the door is closed, and Fig. 6 is a similar view showing the position of the parts 45 when the door is open.

In carrying out our invention we employ a line 5 which leads from some point remote from the door, from which the door is to be 50 operated. At a point at about the elevation of the top of the door the line 5 passes through an eye or other equivalent device 6, beyond which, it is constructed with two branches 7 and 8, the branch 7 passing over

two sheaves 9 and 10 fixed to the door casing 55 adjacent to the hinged side of the door; the sheave 10 being arranged about the same elevation as the door lock.

To the latching spindle of the door lock is rigidly attached an arm 11, to the outer end 60 of which is connected the branch 7 of the line 5 after passing over the sheave 10.

The branch 8 of the line 5 after passing over a pulley 14, is directly attached to the door preferably at its top, as illustrated in 65 Fig. 1. The pulley 14, is freely suspended from the outer end of a bracket 15, the said bracket being fixed above the door to the transom or to the door casing, and operating in connection with the pulley 14 to so direct 70 the branch 8 that when the line 5 is pulled the door, if closed, will be opened, or if the door be opened, a like pull on the line will close it. This operation of the device is best understood by reference to Figs. 5 and 6, 75 wherein it is seen that when the door passes under the extremity of the arm 15 or pulley 14, it is in a neutral position, but the momentum acquired by the door at the beginning of its opening or closing movement, carries it 80 beyond the pulley to a fully open or closed position, as the case may be. It is thus seen that by one and the same operation, the door is both opened and closed.

If the device is applied to a door which is 85 closed by a spring or which is so hung as to swing closed under the influence of gravity, we preferably provide in connection with the door opening means, means for automatically locking the door in open position. 90 This we accomplish by attaching to the wall or other fixed support, a catch 16 having a hook or an angularly turned end, as shown in Fig. 1. This catch is so located that when the door is opened the arm 11 will pass over 95 the top thereof and will engage with its angularly-turned end, as shown in Figs. 2 and 3, when the line 5 is released; thus making it possible to unlock the door, open it, and lock the door in open position by a single operation. When desired to close the door, it is 100 obvious that on drawing on the line 5 sufficiently to carry the arm 11 out of the path of the angularly-turned end of the catch 16, the door will swing to a closed position.

The arrangement and construction of the door fastener while being the preferred embodiment of our invention, may be modified 105

in numerous particulars within the scope of the invention as defined in the claims annexed.

Having thus described our invention, we claim as new and desire to secure by Letters 5 Patent:

1. In combination with a door having a lock, an opener therefor comprising a bracket attached to the door casing above the door and extending outwardly therefrom, a pulley 10 suspended from the outer end of said bracket, an arm attached to the latching spindle of the lock, and a single line passing to the point from which the door is to be operated having two branches connected together adjacent 15 to the door, one of which passes over the suspended pulley and is attached to the door, and the other of said branches is connected to said spindle arm.
2. In combination with a door having a lock, an opener therefor comprising a bracket attached to the door casing above the door and extending outwardly therefrom, a pulley suspended from the bracket, an arm fixed to the latching spindle of the lock, sheaves fixed 20 at one side of the door casing, and a line leading to the door having two branches, one for unlatching the door, passing over said sheaves and attached to said arm, and the other for moving the door to and from closed 25

position, passing over said suspended pulley 30 and connected with the door.

3. In combination with a hinged door having a revoluble latching spindle, an opening and closing device for the door comprising a support arranged outwardly from the door 35 intermediate its side edges, a flexible member attached to a fixed part of the door near the top of the free edge thereof and movably connected with said support, whereby when said member is pulled, that portion of the member 40 between the door and support will pass through the support as the door swings toward the support, and the said member will pass through the support in the opposite direction as the door swings past and from the 45 support, an arm attached to the latching spindle, and a second flexible member connected to the first mentioned flexible member and to said arm for operating the latching spindle.

In testimony whereof we have signed our names to this specification in the presence of two subscribing witnesses.

PETER D. GALARNEAU.
WILLIAM S. NEWTON.
